CONVERSION OF HYDROCARBONS

Friedrich W. Leffer, Kenton-Harrow, England, assignor to Universal Oil Products Company, Chicago, Ill., a corporation of Delaware

Application October 21, 1937, Serial No. 170,186

4 Claims. (Cl. 196—10)

This invention relates particularly to the conversion of the heavier fractions of petroleum and analogous fractions from other hydrocarbonaceous materials into substantial yields of high antiknock motor fuel.

In a still more specific sense the invention is concerned with processes wherein heavy hydrocarbon mixtures are subjected to pyrolytic conditions of temperature and pressure to produce gases containing appreciable percentages of olefinic hydrocarbons, liquid motor fuel fractions, intermediate insufficiently converted fractions suitable for further subjection to pyrolysis and heavy residues which are unsuitable therefor. It is a particular object of the present invention to utilize the olefinic content of the fixed gases to produce additional yields of liquid motor fuel fractions and to selectively treat by suitable chemical processes the heavier and the lighter fractions respectively of the motor fuel fractions produced both in the primary pyrolysis and in the subsequent selective polymerization step.

In accordance with the need for increased efficiency in the utilization of petroleum and particularly in the more efficient utilization of the products from the cracking of petroleum, considerable research is being devoted to the development of processes which will effectively reconvert at least a portion of the gaseous by-products of cracking back into normally liquid hydrocarbons utilizable as motor fuel. At the present time these developments have reached the stage of utilizing the olefinic content of the cracked gases by subjecting them to polymerization processes, the majority of which are effective in converting the major portion of the propylene and butylenes without much effect upon the ethylene content although this may be equivalent in volume to the total of the 3 and 4 carbon atom hydrocarbons mentioned. Strictly thermal methods of polymerization as well as those employing specific catalytic materials are in commercial use and are apparently still on a competitive basis. The present process, the features of which will be developed in the following specification, embodies an improvement in methods of catalytic polymerization of the lighter olefinic hydrocarbons produced in cracking hydrocarbon oils, utilizing particular types of catalytic materials and selected conditions of treatment for the various olefin-containing fractions both of the gases and the motor fuel boiling range liquids, while applying also selected

methods of chemical treatment best suited to the cracked and polymer fractions respectively.

In one specific embodiment the present invention comprises cracking hydrocarbon oil mixtures to produce material yields of gasoline and olefin containing gases, fractionating the gasoline into light and heavy portions respectively, treating said heavy portions with sulfuric acid to improve their quality, subjecting the gases and the lighter gasoline fractions to contact with phosphoric acid containing catalysts to effect polymerization, alkylation and treating reactions, stabilizing the products of these reactions to a given vapor pressure, treating the stabilized material with relatively mild chemical reagents, blending the treated material with the sulfuric acid-treated heavier fractions of the gasoline and fractionating the blended material to produce a refined high antiknock motor fuel as the product of the process.

In an alternative embodiment the gases and lighter gasoline fractions are first separated by condensing the former, the separated gases are separately contacted with phosphoric acid-containing catalysts at temperatures and rates favorable to the selective polymerization of their butylene content, the butylene polymers are separated from the residual gases and the re-vaporized light gasoline fractions are separately contacted with phosphoric acid-containing catalysts along with the residual gases.

The various cooperative features of the present process which render it novel and useful from a commercial standpoint will be developed in greater detail by following a characteristic process flow in connection with the attached drawing which shows in general side elevation by the use of conventional figures an arrangement of apparatus in which the process may be conducted. In the development of the process, several alternative modes of operation will be shown which are all comprised within the general scope of the invention.

Referring to the drawing, line 1 containing valve 2 is shown as an inlet line for vaporous cracked products to a final fractionator 3, the details of the cracking operation having been omitted as constituting no special feature of the present invention since the vaporous products from practically any commercial type of cracking process may be subjected to the present type of treatment. Fractionator 3 is preferably divided by a capped collecting plate 5 into upper section 4 and lower section 6, the lower section having a draw line 7 containing valve 8 for the removal

of intermediate fractions which usually are returned to the cracking process to undergo further conversion in admixture with the original charging stock.

5 According to the present process, the fractionation is so conducted that only gases and gasoline boiling range materials are admitted to section 4, the heavier portions of the gasoline accumulating on collecting plate 5 and being 10 continuously withdrawn therefrom through a line 80 containing valve 81 to an appropriate type of chemical treatment which will be subsequently described. The vapors from upper section 4 of fractionator 3 will comprise the total 15 fixed gases and the lower boiling constituents of the gasoline product which will have a boiling range depending upon such factors as the type of oil originally cracked, the conditions of cracking, the hydrocarbon group content of the 20 light fraction, particularly in regard to olefins and other more reactive hydrocarbons, the nature and proportioning of the olefins in the fixed gases and the character desired in the finished product of the process. In other words, 25 it will be a matter of trial in different cases to determine the best segregation between the light and heavy gasoline fractions.

At this point several alternative modes of procedure are possible. In one case the total mixture of gases and light gasoline fractions may be subjected to a catalytic treatment aimed at effecting polymerization and other types of reactions among the hydrocarbons including a refining action, while utilizing a portion of the 35 condensable overhead fractions to assist in controlling the boiling range of the overhead products. In another alternative mode of operation the light gasoline fractions are condensed and separated from the fixed gases, the gases are 40 then separately subjected to catalytic polymerization for the removal of a portion of the more readily polymerizable olefins and the residual gas mixture containing unconverted gaseous olefins are then admixed with the revaporized light gasoline 45 fractions and subjected in admixture to separate catalytic action to produce reactions of a different character all aimed at the selective utilization of the gaseous olefins to produce increased yields of gasoline.

50 Thus in one instance the total products from the top of fractionator 3 may be passed through line 9 containing valves 10 and 11 to contact with solid polymerizing catalysts whose manufacture and properties will be described later, said catalytic material being contained in treaters 31 and 55 34 connected by a line 32 containing a valve 33, these two treaters representing any number which may be employed in series connection for effecting the desired polymerization reactions. 60 In this type of operation a sufficient amount of the overhead products may be diverted to undergo partial condensation and produce an overhead reflux to assist in controlling the boiling point of the overhead fraction, said diverted 65 stream following line 12 containing valve 13, condenser 14, run down line 15 containing valve 16 and entering receiver 17 from which the condensed liquids are withdrawn by pump 20 through line 18 containing valve 19 and returned 70 by way of line 21 containing valve 22 and line 23 containing valve 24 to the upper portion of the fractionator. The gases accumulating in receiver 17 are then taken by pump or compressor 28 through line 26 containing valve 27 and discharged through line 29 containing valve 30 back 75

to line 9 and thence into contact with the polymerizing catalyst.

It is a feature of the present process that the first polymerizing unit comprising as shown in the drawing towers 31 and 34 should be operated at relatively low temperature to effect the selective polymerization of the more readily polymerizable olefins in the gases and in the light gasoline fractions, the preferred temperature range when using the particular catalysts characteristic of the invention being of the order of from 90 to 120° C. At this temperature and under the normal pressures of such polymerizing process which normally range from approximately 100 to 300 lbs. per square inch, there is a more or less selective polymerization of the butylenes and particularly isobutylene, so that there is produced a relatively high yield of octenes from the butylenes present in the gases. There will also be some polymerization of the olefinic content of the light gasoline fraction so that in effect there is a general rise in the boiling point range.

In order to bring the mixture of gases and light gasoline vapors to the proper temperature for treatment in the primary catalytic unit comprising chambers 31 and 34, a cooler is provided since obviously in case the mixture is brought directly from the fractionator of the cracking plant with diversion only of a sufficient portion of the mixture to furnish reflux for the fractionating column, the temperature will be higher than desired since it may vary from approximately 150 to 260° C. depending upon the pressure obtaining at the top of the fractionator and the average boiling range of the emergent gas-vapor mixture. In order to reduce the temperature to within the approximate range specified above, any required portion of the gas-vapor mixture may be diverted through line 13' and 40 valve 12' through cooler 14' and back into line 9 by way of line 15' containing valve 16'. The cooler may be cooled by air or any other fluid or liquid which is suitable for effecting the required reduction in temperature. Obviously, some temperature reduction is effected in the total gas-vapor mixture by the condensation of the required reflux since the residual gas mixture passing through line 29 back to line 9 will be at approximately normal atmospheric temperature. 50

The total products from the primary polymerizing step follow line 35 containing valve 36 and pass through a condenser 37 which has a rundown line 38 containing valve 39 and leading to a receiver 40 which functions as a separator 55 for the liquid and gaseous products, the further treatment of which will be presently described. In an alternative mode of operation the products from the fractionator are all passed through line 12 and valve 13 with valve 11 in line 9 closed so 60 that the normally gaseous and the normally liquid products are separated in receiver 17 and separately contacted with the catalyst. In this case the gases follow line 26, valve 27, pump 28, line 29 and valve 30 to the primary polymerizing unit as before but without admixture with the normally liquid light gasoline fractions. By this procedure the conditions necessary for effecting maximum polymerization of the butylene content of the gases may be more accurately defined 65 and products containing a higher percentage of octenes (which are readily hydrogenatable to iso-octane) produced. The adoption of this mode of procedure will obviously depend upon the butylene (and particularly the isobutylene) con- 70 75

tent of the gases and the proportioning of the different groups of hydrocarbons in the gases and the light gasoline fractions. Obviously when all of the gas-vapor mixture from line 9 is subjected to cooling in condenser 14, the residual gases will require reheating to the optimum temperature for the polymerization of the more readily polymerizable olefins although means for accomplishing this reheating are not shown in the drawing.

In this second method the vapors of the light gasoline fractions are subjected to catalytic action along with the residual gases from the primary polymerizing step, that portion of the gasoline vapors not needed for fractionation control passing along line 21 through valve 27' to the second treating unit comprising treaters 51 and 54 connected by line 52 containing valve 53 and representing as in the case of the primary unit any desired number and arrangement of treating towers. Since the light gasoline fractions passing through line 21 to the second catalytic treating unit will require vaporizing and heating to an optimum temperature for treatment, a portion or all thereof may be diverted through line 22' and valve 23' to heater 24' and back to line 21 by way of line 25' containing valve 26' with proper setting of valve 27' to cause the required diversion. The residual gases from receiver 40 follow line 46 containing valve 47 to pump or compressor 48 and are discharged through line 49 containing valve 50 into line 21 to undergo simultaneous treatment with the light gasoline vapors. In the second treating unit the temperature preferably employed is within the approximate range of 150-250° C. which is more favorable to the polymerization of residual propylene and normal butylenes and also to the furtherance of alkylation and condensation reactions between said olefins and the reactive hydrocarbons in the light gasoline fractions which may comprise n- and iso-olefins, cyclo olefins and aromatics depending upon the nature of the stock originally cracked and the intensity or depth of the cracking process. By utilizing the higher temperatures in the second treating unit the optimum utilization of the more difficultly polymerizable olefins and the treating of the light gasoline fractions for the removal of more highly unsaturated gum-forming hydrocarbons is advantageously effected.

The total products from the reactions in the second treating step leave final treater 54 through line 55 containing valve 56 and pass through a condenser 57 which has a line 58 containing valve 59 leading therefrom to a receiver 60 which functions as a gas-liquid separator and permits the withdrawal of gases through line 66 containing valve 67, the gases at this point consisting principally of ethane, ethylene, methane, hydrogen, and other gases such as hydrogen sulfide in case this was present in the primary gas mixture.

The liquid products from both treating units are now blended and stabilized, those from receiver 40 passing through line 41 and valve 42 to pump 43 which discharges into line 44 containing valve 45 and leading to stabilizer 68, while those liquid products accumulating in receiver 60 are removed through line 61 containing valve 62 and taken by pump 63 to be discharged through line 64 containing valve 65 and into line 44 and thence to the stabilizer. The function of stabilizer 68 is to remove substantially all 3-carbon atom hydrocarbons and a sufficient quantity of the 4-carbon atom hydrocarbons to reduce the

vapor pressure of the polymer products to a point conforming to specifications which is usually within the range of 8-12 lbs., per sq. in. when determined by the Reid vapor pressure method. While other devices may be employed including overhead cooling and refluxing, the drawing shows merely a reboiling coil 71 for maintaining a sufficient temperature to cause the effective fractionation and separation of the undesirable 3- and 4-carbon atom hydrocarbons which are evolved through line 69 and valve 70 to whatever disposition may be desired. The stabilized polymer products follow line 72 containing valve 73, pass through cooler 74 and thence through run down line 75 containing valve 76 to a pump 15 77 which discharges into a line 78 containing a valve 79 and leading to the second chemical treating unit to be presently described.

The primary chemical treatment consists in the application of sulfuric acid to the heavier gasoline fractions which leave cracking plant fractionator 3 from collecting plate 5 and follow line 80 containing valve 81 to the receiver 82 which has a conventional gas release line 83 containing a valve 84. The liquid is taken by pump 87 through line 85 containing valve 86 which discharges through line 88 containing valve 89 into some type of mixer or agitating device 92 after having received an addition of sulfuric acid through line 90 containing valve 91, the amount and concentration of the acid being selected to produce the best overall treating effect when considering the chemical characteristics of the heavier fractions. The mixture of treated oil and sludge acid passes through a line 93 and valve 94 to a separator 95 from which sludge is drawn through line 96 and valve 97, the treated fraction still somewhat acid passing through a line 98 containing valve 99 to a water washing tower 100 into which a water spray is introduced through line 103 containing valve 104 and from which acid wash water is drawn from the bottom of the tower through line 101 containing valve 102. The washed and possibly slightly acid stock is then passed through line 105 containing valve 106 to a pump 107 which discharges through a line 108 containing a valve 109 to line 116 leading to the mixing device of the second chemical treating unit.

The second unit is operated primarily to give a light treatment to the products from the catalytic treating units which accumulate in the receiver 110 having a conventional gas release line 111 containing a valve 112 although there is usually little tendency for gas accumulations at this point.

The liquid polymer products taken through line 113 containing valve 114 are discharged by pump 115 through line 116 containing valve 117 and thence into the mixer of the secondary unit 60 after receiving the primary acid treated and washed heavier fractions from line 108 and a definite amount of alkali (usually caustic soda) from line 119 containing valve 120. As a rule the alkali treatment is all that is necessary for refining the polymer products and sufficiently neutralizing the acid treated stock. If the polymer product contains appreciable percentages of mercaptans and is sour to the doctor test, a plumbite or other sweetening method may be substituted with suitable modification of the subsequent treating equipment. If desired, although not shown in the drawing, the acid treated fraction from the primary chemical treating unit may be separately neutralized although provision for 75

this has been omitted from the drawing in the interest of space economy.

The mixture of oil and treating reagent from mixer 121 flows through line 122 containing valve 123 to a settler 124 from whence spent aqueous layer is withdrawn through line 125 and valve 126 while the treated oil which may now be slightly alkaline passes through line 127 containing valve 128 to a final washing tower 129 which 10 again has a line 132 containing a valve 133 and an inlet water spray and a line 130 containing a valve 131 for drawing off wash water.

As a final step in the process the blended and treated products are fractionated to produce 15 a gasoline of desired boiling range. Thus the finally washed blend is withdrawn from the top of tower 129 through line 134 containing valve 135 and forced by pump 136 through a line 137 containing valve 138 through a heater coil 138' 20 which serves to bring the products up to a temperature which will insure their proper fractionation. The heated material passes through line 139 containing valve 140 to a final fractionator 141 from which the desired gasoline 25 product is taken overhead in vapor form, the vapors following line 144 containing valve 145 and passing through condenser 146 and liquid rundown line 147 containing valve 148 to final receiver 149 which has a conventional gas release line 150 containing a valve 151 and a draw line 152 containing a valve 153 for finished product. Heavy products separated in fractionator 141 are withdrawn through line 142 having valve 143.

The catalytic treating material preferably employed in the catalytic treating units described above comprises preferably a granular composite produced by primarily incorporating a phosphoric acid with a relatively inert carrying material such as kieselguhr, heating the primary pasty mix to a temperature of the order of 300° C. or higher to produce a solid cake, grinding and sizing the cake to produce particles of approximately 6-20 mesh and if found necessary subjecting the granular particles to the action of superheated steam at a temperature of the order of 45 260° C. under atmospheric pressure to produce the optimum degree of hydration. The above procedure may be modified by forming the original pasty mix either by extrusion or pelletizing 50 methods and calcining and steaming the forms. Catalytic materials of this character comprise a certain amount of active phosphoric acid of a somewhat greater degree of hydration than the pyro acid and evidently some silico-phosphoric acid complexes which have some catalytic and 55 treating activity and furnish a support for the more active phosphoric acid constituent. Materials of this character have been found to be 60 specially active in effecting polymerization and other reactions among olefinic and other unsaturated hydrocarbons with a minimum of undesirable side reactions and are specially easily regenerated after a period of service by burning off carbonaceous deposits by means of air of combustion gas mixtures containing regulated percentages of oxygen. After such reactivation 65 which may employ temperatures of the order of 500° C. it is practically always necessary to rehydrate the particles as in the method of manufacture and reactivated materials are frequently found to have higher catalytic activity than freshly prepared catalysts.

The following example is given to indicate the character of the results obtainable by the use of

the process although not with the intention of correspondingly limiting its scope.

A gas oil fraction representing an intermediate cut from a mixed crude oil from the Mid-Continent area was cracked at a temperature of approximately 500° C. in the cracking zone under a pressure of approximately 350 lbs. per sq. in., the vapors being fractionated in accordance with the scheme outlined in the preceding process description so that approximately the lighter half 10 of the gasoline boiling range material was removed from the top of the fractionator along with the normally gaseous products while the heavier half was removed from the upper section of the fractionator and passed directly to 15 sulfuric acid treatment. The overhead in the fractionator was cooled and the light gasoline vapors condensed. The residual gas mixture was reheated to a temperature of approximately 110° C. and passed through a series of chambers 20 containing solid phosphoric acid catalysts to polymerize substantially all of the isobutylene content and a portion of the normal butylenes. The portion of the condensed light gasoline fraction not required as reflux at the top of the fractionating column was reheated to a temperature of approximately 260° C. and mixed with the residual gases after the removal of the butylene polymers, the resulting temperature of the gas-vapor mixture entering the second catalytic unit 30 being 225-230° C., which effected a polymerization of the major portion of the residual 3 and 4 carbon atom olefins, some alkylation reactions among the hydrocarbons and a small degree of polymerization of the normally liquid olefinic 35 hydrocarbons, particularly those of a conjugated diolefinic character. The combined primary polymers plus secondary polymers and treated light gasoline vapors were combined and stabilized to a 10 lb. Reid vapor pressure.

The higher boiling 50% of the gasoline was treated with sulfuric acid at the rate of approximately 5 lbs. per 42 gallon barrel and the stabilized mixture of polymers and treated light ends were treated with 10° Bé. caustic soda in 45 admixture with the washed heavy fraction.

The net result of the foregoing series of operations was the production from the original gas oil of 65% by volume of 400° F. end point gasoline having an octane number of 72 by the motor method and passing all specifications in respect to gum and sulfur content.

The character of the present invention and its novelty and utility in the petroleum refining art can be seen from the preceding specification and numerical sections although neither is intended to be unduly limiting.

I claim as my invention:

1. A process for treating the mixture of gasoline vapors and normally incondensable gases produced in the cracking of hydrocarbon oil, which comprises separating said mixture into a heavy gasoline fraction, a light gasoline fraction and a gaseous fraction, subjecting said heavy gasoline fraction to a refining treatment with sulfuric acid, subjecting said gaseous fraction to contact with a phosphoric acid-containing catalyst to effect selective polymerization of the butylenes therein contained, condensing and separating liquid polymers from unconverted gases, combining the latter with said light gasoline fraction and subjecting the resultant mixture to separate contact with a phosphoric acid-containing catalyst to effect further polymerization and treatment of the mixture, stabilizing gasoline 75

boiling products of both said polymerizing stages in admixture, combining the stabilized mixture with the acid treated heavy gasoline fraction and subjecting the resultant blend to treatment with 5 alkaline materials.

2. A process for treating the mixture of gasoline vapors and normally incondensable gases produced in the cracking of hydrocarbon oil, which comprises separating said mixture into 10 a heavy gasoline fraction, a light gasoline fraction and a gaseous fraction, subjecting said heavy gasoline fraction to a refining treatment with sulfuric acid, subjecting said gaseous fraction to contact with a phosphoric acid-containing catalyst at temperatures of the order of 90 to 120° C. to effect selective polymerization of the butylenes therein contained, condensing and separating liquid polymers from unconverted gases, combining the latter with said light gasoline fraction 15 and subjecting the resultant mixture to separate contact with a phosphoric acid-containing catalyst at temperatures of the order of 150 to 250° C. to effect further polymerization and treatment of the mixture, stabilizing gasoline boiling products of both said polymerizing stages in admixture, combining the stabilized mixture with the acid treated heavy gasoline fraction and subjecting the resultant blend to treatment with alkaline materials.

3. In the cracking of hydrocarbon oil where-in gasoline distillate is separated from normally incondensable gases containing butenes and propene, the method which comprises subjecting the separated gas to polymerization under conditions suitable for selective polymerization of butenes, separating resultant butene polymers from the residual propene-containing gas, combining the latter with at least a portion of said gasoline distillate, including the lighter fractions 10 thereof, and subjecting the resultant mixture to propene polymerizing conditions.

4. A process for treating the mixture of gasoline vapors and normally incondensable gases produced in the cracking of hydrocarbon oil, 15 which comprises separating from said mixture a heavy gasoline fraction, a lighter gasoline fraction and a normally gaseous fraction containing butenes and propene, subjecting the gaseous fraction to polymerization under conditions suitable for selective polymerization of butenes, separating the resultant butene polymers from residual propene-containing gas, combining the latter with said lighter gasoline fraction and subjecting the resultant mixture to propene poly- 20 25 merizing conditions.

FRIEDRICH W. LEFFER.
